VACUUM CLEANER

Carl Oskar Ernolff, Stockholm, Sweden, assignor to
Electrolux Corporation, New York, N. Y., a corporation of Delaware

Application December 7, 1938, Serial No. 244,308
In Sweden December 11, 1937

4 Claims. (Cl. 285—175)

My invention relates to vacuum cleaner and more particularly to means for connecting a flexible hose to the vacuum cleaner casing.

In vacuum cleaners of the so-called inside bag type, an inlet opening is usually provided at one end and an outlet opening at the other end of the casing. For ordinary cleaning, a flexible hose is connected in the inlet opening. However, it is sometimes desirable to use a blowing action, at which time the hose is connected in the outlet opening.

An object of my invention is to provide an improved means for facilitating the connection and disconnection of the hose to the inlet and outlet openings.

Another object of my invention is to provide an improved bayonet type locking means for rigidly securing the hose in the inlet and outlet openings.

What I consider to be novel and my invention may be better understood by reference to the following specification and appended claims when considered in connection with the accompanying drawing, in which

Fig. 1 is a side elevation of the vacuum cleaner casing broken away in part to show the securing means for the flexible hose;

Fig. 2 is an enlarged detail view showing the hose connected in the outlet opening;

Fig. 3 is an enlarged view of the securing means located in the outlet opening;

Fig. 4 is a plan view of the securing means; and

Fig. 5 is an enlarged plan view of a spring secured to the hose.

Referring to the drawing, 10 indicates a vacuum cleaner casing provided with a cover 11 at one end and a housing 12 at the other end, an inlet opening 13 is provided in the cover 11 and an outlet opening 14 provided in the housing 12. In the normal operation of the vacuum cleaner, air is drawn in through the inlet opening 13 and exhausted through the outlet opening 14. A flexible hose 15 is shown in Fig. 1 connected in the inlet opening 13.

When it is desired to use the blowing action of the vacuum cleaner, the hose 15 is disconnected from the inlet opening 13 and connected in the outlet opening 14. In Fig. 2, the hose 15 is shown connected in the outlet opening 14. Secured in the inlet and outlet openings are similar locking rings 16. Rings 16 are provided with three sectors 17 having surfaces 18 inclined upwardly from the two ends toward the center where a radially extending groove 19 is located.

Between the sectors 17, openings 20 are provided. One ring 16 is secured in the outlet opening 14 as by means of a forced fit. Another ring 16 is secured in the opening 13 of cover 11.

Hose 15 is provided with an inner metallic sleeve 21 and an outer metallic sleeve 22. Sleeves 21 and 22 may be secured together beyond the end of hose 15 as by means of welding. Extending over the outer sleeve 22 is a rotatable connecting member 23. An inwardly extending flange 24 of connecting member 23 overlaps an outwardly extending flange 25 of sleeve 22. A ring 26 of resilient material is located between the flanges 24 and 25. Secured to the outer end 15 of connecting member 23 are three pins 27. Pins 27 are adapted to be inserted in the openings 20 between the sectors 17. By rotating the connecting member 23 in either a clockwise or counter-clockwise direction, the pins 27 are caused to ride up the inclined surfaces 18 to a position seated in the grooves 19.

When the pins 27 are seated in the grooves 19, the flexible hose 15 is locked in position in either the opening 13 or 14, as the case may be. For resiliently holding the flexible hose 15 in position, an outwardly extending flange 28 is secured, spaced from the end of connecting member 23 and provided with a U-shaped ring 29 of non-metallic material. Within the ring 29, an annular spring 30 is provided and located to the left of the flange 28, as shown in Fig. 2. Spring 30 is provided with a plurality of outwardly bent elastic fingers 31. When the hose 15 is secured to the ring 16, ring 29 urged by spring 30 engages the opposite side of ring 16 from the side engaged by the pins 27.

When connecting hose 15 into either the inlet opening 13 or the outlet opening 14, the pins 27 are inserted in the openings 20 between the sectors 17. The spring 30 is compressed and the connecting members 23 rotated in either a clockwise or counter-clockwise direction. The pins 27 ride up the inclined surfaces 18 until the pins reach the grooves 19. The compression of spring 30 is somewhat relaxed but is sufficient to hold the pins 27 in the grooves 19. The spring 30 insures a tight connection between the hose 15 and the vacuum cleaner.

To disconnect the hose 15 from the vacuum cleaner, spring 30 is compressed and then the connecting member 23 rotated slightly around in either a clockwise or counter-clockwise direction until the pins 27 register with the openings 20. The hose 15 may then be removed by a longitudinal movement.

What I claim is:

1. The combination with a vacuum cleaner casing having an opening and a flexible hose, of means for securing the flexible hose in the opening of the vacuum cleaner casing including a ring having a plurality of spaced sectors, said sectors having transversely extending grooves, said ring being secured in the opening of the casing, outwardly extending pins secured to the end of the hose, and resilient sealing means secured between the hose for holding said pins in engagement with said grooves and for sealing said hose with respect to said casing.
2. The combination with a vacuum cleaner casing having an opening and a flexible hose, of means for securing the hose in the opening of the vacuum cleaner casing including a ring having a plurality of spaced sectors secured in the opening, said sectors having transversely extending grooves, outwardly extending pins secured to the end of the hose, a compressible packing secured around the hose and spaced from the end, and resilient means associated with said compressible packing for resiliently holding the hose in engagement with the vacuum cleaner when the pins are seated in said grooves and for compressing said packing against the exterior of said casing.
3. The combination with a vacuum cleaner casing having an opening of means for detachably securing a flexible hose in the opening of a

vacuum cleaner casing including a ring secured in said opening having a plurality of sectors with spaces therebetween, said sectors having transverse grooves, a connector rotatably mounted on said hose, outwardly extending pins radially spaced around said connector, a flange secured to said connector spaced from its end and from said pins, a non-metallic U-shaped ring loosely mounted on said flange, and a spring located within said ring abutting the side of said flange adjacent to said pins for holding said pins in said grooves and sealing said hose in the opening of said casing.

4. The combination with a vacuum cleaner casing having an opening, of means for detachably securing a flexible hose in the opening including a ring secured in said opening having a plurality of sectors with spaces therebetween, said sectors having transverse grooves, a connector rotatably mounted on said hose, outwardly extending pins radially spaced around said connector, a flange secured to said connector spaced from its end and from said pins, an annular spring having outwardly bent elastic fingers abutting the side of said flange adjacent said pins, and a U-shaped non-metallic ring inclosing said spring and said flange for holding said pins in said grooves and sealing said hose in the opening of said casing.

CARL OSKAR ERNOLF.
